(57) **CLAIM**

The ornamental design for a lifter for washing machine, as
shown and described.

DESCRIPTION

FIG. 1 is a front perspective view of a lifter for washing
machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is a cross-sectional view thereof, taken along line 9-9
in FIG. 6;

FIG. 10 is a cross-sectional view thereof, taken along line
10-10 in FIG. 6;

FIG. 11 is an enlarged view of the encircled portion 11 in
FIG. 1;

FIG. 12 is an enlarged view of the encircled portion 12 in
FIG. 2;

FIG. 13 is an enlarged view of the encircled portion 13 in
FIG. 4;

FIG. 14 is an enlarged view of the encircled portion 14 in
FIG. 9; and,

FIG. 15 is an enlarged view of the encircled portion 15 in
FIG. 10.

The dot-dash broken lines encircling enlargement portions
of the lifter for washing machine form no part of the claimed
design.

1 Claim, 11 Drawing Sheets
